(57) **CLAIM**

The ornamental design for a manipulative learning device, as shown and described.

DESCRIPTION

FIG. 1 is a perspective view of a manipulative learning device in accordance with my new design;

FIG. 2 is a front elevational view of the manipulative learning device of FIG. 1;

FIG. 3 is a rear elevational view of the manipulative learning device of FIG. 1;

FIG. 4 is a side view thereof;

FIG. 5 is an opposite side view thereof;

FIG. 6 is a plan end view thereof; and,

FIG. 7 is a bottom view thereof.

The portions of the manipulative learning device depicted in broken lines in FIGS. 1-6 form no part of the ornamental design.
